UNITED STATES PATENT OFFICE.

GEORGE W. BARIAN, OF FOWLERVILLE, MICHIGAN.

FIREMAN'S SAFETY-HELMET.

SPECIFICATION forming part of Letters Patent No. 439,093, dated October 28, 1890.

Application filed March 1, 1890. Serial No. 342,294. (No model.)

To all whom it may concern:

Be it known that I, GEORGE W. BARIAN, a citizen of the United States, residing at Fowlerville, in the county of Livingston and State 5 of Michigan, have invented certain new and useful Improvements in Firemen's Safety-Helmets, of which the following is a specification, reference being had therein to the accompanying drawings.

10 This invention relates to new and useful improvements in safety-helmets for firemen; and the invention consists in the peculiar construction of a helmet or mask designed to cover the face of the fireman, means for securing it in position and for making a tight fit around the head, an air-tank connected with the mouth-piece in said mask, and valves to control the air-supply from the air-tank to the mouth of the wearer and from the mouth 15 of the wearer to the outside for exhalation, and, further, in the peculiar construction and combination of the necessary parts, all as more fully hereinafter described.

In the drawings which accompany this specification, Figure 1 is a side elevation of my improved device as in use. Fig. 2 is a front elevation thereof detached. Fig. 3 is a vertical central section through the mouth-piece and valves.

20 A is the helmet or mask, preferably of leather, rubber, or other flexible material, and of suitable shape to conform to the front of the head of a person and to make a tight joint over the top of the head and at the sides. B are tightening-strings secured in the edges of this mask to tighten it around the head of the wearer, and C C' are securing-straps passed over the top and back of the head, respectively, to hold the mask firmly 25 in position.

25 D is a frame, preferably a metal frame, secured in the front of the mask and holding a suitable transparent body E—such as glass—opposite the eyes of the wearer.

30 F is a shield, preferably of metal, secured in the lower part of the mask, forming a plate to support the mouth-piece and valves.

35 G is a tube passing through the shield F and secured therein, to the inner end of which is secured the mouth-piece H, preferably by means of an intermediate flexible tube I, and at its outer end this tube G carries the sleeve

J, having a suitable cap through which the handle K of the valve L passes. This valve L is preferably made as shown, consisting of 55 a tube a, engaging in the end of the tube G, and provided with suitable perforations b and a cap c. The valve L is normally closed by the tension of the spring d. The tube G on its lower side is provided with a suitable 60 nipple e, which connects with the air-tank M by means of the flexible tube N. This air-tank M may be of any suitable construction, either in the shape of a garment to be worn upon the body of the fireman, in the shape of 65 a bag having suitable means for supporting it, or in any other desired form. The connection between the tube G and the air-tank M is normally closed by the valve O, which has a stem P extending through the tube G, and 70 having the bearing f, against which the spring g acts to keep the valve in its closed position. h is a hollow packing-nut which forms a chamber for the spring.

75 Q is a three-way cock secured in the flexible tube N at any suitable point, its apertures being adapted to register in the tube or with the lower opening in the tube and the aperture i through the casing of the cock through which the tank may be filled. 80

The parts being thus constructed, they are intended to operate as follows: In case of fire, where the firemen are obliged to enter the rooms filled with dense smoke, the mask is secured upon the head by means of the 85 straps C C' and the tight connection with the head by means of the drawing-strings B at all points, the tank M being previously filled with air through the apertures i. The valves L and O being normally closed, the wearer 90 when he desires to inhale presses with his finger upon the valve-stem P, thereby opening the valve O and drawing the air from the tank. When he desires to exhale, he releases his hold of the valve-stem P, which is at once 95 closed by tension of the spring g, and by the force of his exhalation opens the valve L, allowing his breath to escape through the aperture k in the end of the sleeve J. In case of urgent necessity, should the tank M require 100 to be filled the fireman may go to any convenient point where fresh air can be obtained and open the valve L, draw in his breath, close the valve L, open the valve O, and ex-

hale into the tank. A number of repetitions of this process would soon fill the tank and put it in condition to be used again; but I preferably fill the tank with pure air by a 5 pump or other suitable means through the aperture *i*.

It will be seen that my device can be applied almost instantly, can be as readily removed, is light, forms a protection to the face 10 of the fireman against heat, does not obstruct his view, and gives him an abundant supply of fresh air under the most unfavorable conditions.

By providing the device with the lever *R* 15 the valve *O* may be opened by pressure of the tongue on the knob *S*, thus making the device more nearly automatic and leaving the hands of the wearer free.

What I claim as my invention is—

- 20 1. In a safety-helmet for firemen, the combination, with the mask, of the mouth-piece *H*, tube *G*, supporting the same, valve *L* in the tube, spring *d* for normally holding the valve closed, valve *O*, stem *P* on the same, 25 and spring *g* on the stem, substantially as described.
2. In a safety-helmet, the combination, with a mask, of a tube extending through the

same, a pipe *N*, leading into the tube, having an aperture therein, a three-way valve in the 30 tube, and a tank out of which the tube leads, substantially as described.

3. In a safety-helmet for firemen, the combination, with a flexible mask having drawing-strings, and suitable securing-straps, of a 35 mouth-piece secured in said mask having an external exit-opening normally closed by a spring-controlled valve, an air-supply tank, a connecting-tube between the tank and mouth-piece, and a stem for opening said valve, substantially as described.

4. In a safety-helmet, the combination, with a flexible mask having suitable fastenings, of a valved tube extending through and supported by the mask, a branch extending out 45 from the tube, a valve in said branch having an operating-stem extending beyond the tube, and an extension-tube on the branch, substantially as described.

In testimony whereof I affix my signature, in 50 presence of two witnesses, this 23d day of January, 1890.

GEORGE W. BARIAN.
